(57) **CLAIM**

The ornamental design for the game board apparatus set as shown and described.

DESCRIPTION

FIG. 1 is a left side, top, and front perspective view of the game board apparatus set, in accordance with the present invention, wherein the game board apparatus set is shown in a fully assembled state;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a left side, bottom, and rear perspective view thereof;

FIG. 9 is a left side, top, and front perspective view of the game board apparatus set, wherein the first layer of pieces has been removed from the fully assembled game board apparatus set;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof;

FIG. 16 is a left side, bottom, and rear perspective view thereof;

FIG. 17 is a left side, top, and front perspective view of the game board apparatus set, wherein the first and second layer of pieces have been removed from the fully assembled game board apparatus set;

FIG. 18 is a front elevation view thereof;

FIG. 19 is a rear elevation view thereof;

FIG. 20 is a left side elevation view thereof;

FIG. 21 is a right side elevation view thereof;

FIG. 22 is a top plan view thereof;

FIG. 23 is a bottom plan view thereof;

(Continued)

FIG. 24 is a left side, bottom, and rear perspective view thereof;
 FIG. 25 is a left side, top, and front perspective view of the game board apparatus set, wherein the first and second layer of pieces, along with the grid have been removed from the game board apparatus set;
 FIG. 26 is a front elevation view thereof;
 FIG. 27 is a rear elevation view thereof;
 FIG. 28 is a left side elevation view thereof;
 FIG. 29 is a right side elevation view thereof;
 FIG. 30 is a top plan view thereof;
 FIG. 31 is a bottom plan view thereof;
 FIG. 32 is a left side, bottom, and rear perspective view thereof;
 FIG. 33 is a left side, top, and front perspective view of a first piece, which may be any of the pieces of the first or second layer of pieces of the game board apparatus set;
 FIG. 34 is a front elevation view thereof;
 FIG. 35 is a rear elevation view thereof;
 FIG. 36 is a left side elevation view thereof;
 FIG. 37 is a right side elevation view thereof;
 FIG. 38 is a top plan view thereof;
 FIG. 39 is a bottom plan view thereof;
 FIG. 40 is a left side, top, and front perspective view of the game board apparatus set, with the first layer of pieces, the second layer of pieces, row members of the grid, column members of the grid, and base separated;
 FIG. 41 is a second left side, top, and front perspective view of the game board apparatus set, with the first layer of pieces, the second layer of pieces, row members of the grid, column members of the grid, and base separated; and,
 FIG. 42 is a cross section of the fully assembled game board apparatus set taken along the line 42-42 shown in FIG. 41. The dot-dash arrows are used to identify the cross-section views, are for reference purposes only, and form no part of the claimed design.
